(57) CLAIM

The ornamental design for a wrist brace, as shown and described.

DESCRIPTION

FIG. 1 is a front left rear perspective view of the wrist brace, showing our new design, shown in use in a fastened position;

FIG. 2 is a front elevation view thereof, shown in use in the fastened position;

FIG. 3 is a rear elevation view thereof, shown in use in the fastened position;

FIG. 4 is a left side elevation view thereof, shown in use in the fastened position;

FIG. 5 is a right side elevation view thereof, shown in use in the fastened position;

FIG. 6 is a top plan view thereof, shown in use in the fastened position;

FIG. 7 is a bottom plan view thereof, shown in use in the fastened position;

FIG. 8 is another front left rear perspective view, shown in use in an unfastened position;

FIG. 9 is another front elevation view thereof, shown in use in the unfastened position;

FIG. 10 is another rear elevation view thereof, shown in use in the unfastened position;

FIG. 11 is another left side elevation view thereof, shown in use in the unfastened position;

FIG. 12 is another right side elevation view thereof, shown in use in the unfastened position;

FIG. 13 is another top plan view thereof, shown in use in the unfastened position; and,

FIG. 14 is another bottom plan view thereof, shown in use in the unfastened position.

The even length broken lines shown in the drawings represent stitching which does not form a part of the claimed design.

The uneven length broken lines depict the wrist brace in a condition of use on a right hand, and form no part of the claimed design.
